UNITED STATES PATENT OFFICE.

MAURICE J. WOHL, OF NEW YORK, N. Y., ASSIGNOR TO M. J. WOHL & CO. INC., OF LONG ISLAND CITY, NEW YORK, A CORPORATION OF NEW YORK.

FOCUSING ARC LAMP.

Application filed April 10, 1922. Serial No. 551,288.

This invention relates to arc lamps of the focusing type and particularly to hand operated lamps which are especially designed for use in the photographic studio and for the production of motion picture films.

It is the object of the present invention to provide a lamp for photographic illumination, which is extremely light in weight and therefore may easily be carried from place to place in the studio when placed on a suitable support.

It is another object of the invention to provide a lamp which, although its carbons are fed by hand, requires no careful adjustment by the photographer to produce and maintain an arc.

It is a further object of the invention to provide a relatively small lamp which permits the use of high currents and consequently gives a high candle power.

With these and other objects in view, the invention consists in a novel arrangement of parts and details of construction hereinafter fully described and finally pointed out in the claims.

In the drawings forming a part of these specifications—

Figure I is a side elevation of the lamp mechanism showing the lamp housing in section, on its central vertical plane; some of the parts being broken out to show details otherwise covered.

Figure II is a sectional elevation on the plane indicated by the line II—II of Figure I.

Figure III is a detail plan view of the negative carbon holder on the plane indicated by the line III—III of Figure I.

Figure IV is a plan view of the positive carbon mechanism on the plane indicated by the line IV—IV of Figure I.

Figure V is a front elevation of Figure IV on the plane indicated by the line V—V of that figure and looking in the direction of the arrows.

Figure VI is a side elevation of the negative carbon mechanism partly in section on the plane indicated by the line VI—VI of Figure VII.

Figure VII is a front view of the inclined negative carbon support, seen perpendicular to the inclined carbon of Fig. VI.

Figure VIII is a detail of negative carbon support-bridge.

Figure IX is a side elevation of the complete lamp in its housing.

Referring to Figure I of the drawing, A is the lamp housing suitably supported by a segmental bracket B on a stand or pedestal C. The bracket, and with it the lamp, may 60 swivel about a pivot pin C¹ through an angle of 45° to either side of the vertical line. The front plate A¹ of the lamp housing holds the condenser lens L, and the rear plate A² is provided with a horizontal cylindrical 65 extension A³ closed at its rear end. Near the bottom plate A⁴ of the housing, two parallel horizontal rods D¹ forming a track for the lamp mechanism are held by bosses of the plates A¹ and A². Each rod carries a sleeve 70 D². These two sleeves are joined by a transverse bridge piece D³ from which rises vertically the supporting plate for the positive carbon mechanism E¹, and from which extends horizontally the support for the negative carbon mechanism F¹. To the bridge piece D³ is also fastened, between the rods D¹ a horizontal sliding bar D⁴ which is guided in a bushing of rear plate A² and is 75 provided with a large knob or handle D⁵, outside of the lamp housing. The plate E¹ is joined to a similar but shorter plate E² arranged parallel thereto, by the two track rods E³ and the bottom rod E⁴. The plate E² and the whole positive carbon mechanism are of such size that they can be accommodated in the extension A³ when shifted rearwardly by means of knob D⁵. The bridge E⁶ (see Figure IV) is slidably mounted on rods E³ by means of sleeves E⁵. 80 Plate E⁷ is held insulated on E⁶ and carries the carbon holder check E⁸—E⁹ for the positive carbon electrode E¹⁰ in the focal axis of the lens. The free end of carbon E¹⁰ extends freely through plate E¹ and is 85 guided in the insulated plate E¹¹ which is fastened to the front side of E¹. Plates E⁷ and E¹¹ are joined by the flexible conductor E¹².

The horizontal plate F¹ is bent upwardly 100 in its forward part approximately 45 degrees, and widened transversely in T-shape to form the bracket F² (see Figures I, VI and VII). This bracket carries two inclined track rods F³ on which sleeves F⁴ slide, being joined by bridge F⁶ which carries on its rear side, insulated therefrom, a rectangular yoke F⁷ in which swings the fork S. This 105

fork is a part of a curved lever F^8 and is pivoted on pin F^9 . The lever F^8 is provided at its free end with a weight F^{10} . The bridge F^6 holds in the vertical plane of the lamp axis a shouldered collar F^{11} sliding freely therein for a distance limited by the shoulders a and b . The lower end of this collar is formed into a fork which straddles the lever F^8 ; a pin F^{18} held transversely in this fork limiting the downward movement of this lever. An insulating bushing is held in an axial aperture of collar F^{11} . This bushing forms the upper shoulder a and holds in a tapped axial bore a screw F^{17} which forms the lower end of the negative carbon holder chuck $F^{12}-F^{13}$. This chuck holds the negative carbon electrode F^{14} . The arc forming end of carbon F^{14} is guided in an angular slot in transverse bridge F^{15} held between the upper ends of rods F^3 . This bridge is joined electrically by flexible conductor F^{16} to the lower bridge F^6 .

An endless chain G , (Fig. I) fastened to bridge E^6 at point 6, runs from roller G^1 held in an aperture of plate E^2 , then over roller G^2 in plate E^1 and freely through yoke F^7 and fork 8 of lever F^8 , over roller G^3 in plate F^1 and returns in upward direction. The chain is fastened to yoke F^7 and from there runs over roller G^4 held in plate E^1 (below roller G^2) to roller G^1 and plate E^6 . Between rollers G^4 and G^1 a helical tension spring G^5 is slipped over the chain to hold it taut on the various rollers. The ends of the spring are held in extended position by two of the chain links, between which the chain is slack within the coil of the spring. The end of a second chain H is fastened by means of an eye H^1 to the upper face of one prong of the fork 8 of lever F^8 . This chain runs over roller H^2 mounted on the same axis with roller G^2 in an aperture of plate E^1 . From there it runs over roller H^3 mounted on rear plate A^2 and through an aperture in this plate to the outside of the housing, it depends vertically therefrom and terminates in a little weight H^4 which forms a handle.

Current enters the lamp through a cable, the ends of which are connected to terminals J , on plate E^{11} , of the positive and K on plate F^{15} of the negative carbon supports. The operation of this lamp is as follows: Assuming the points of the carbon electrodes to be far apart, a pull on the weight H^4 and chain H will swing lever F^8 on pin F^9 , lifting weight F^{10} until the lever strikes the face c of collar F^{11} . The same pull will then cause the bushing F^{11} to slide upwardly in F^6 until shoulder b strikes the lower face thereof, which also pushes the negative carbon electrode upwardly. The still continued pull on chain H causes the bridge F^6 and sleeves F^4 to move upwardly on the rods F^3 until the negative carbon strikes the positive

carbon E^{10} . If the hand is now removed from weight H^4 , the lever F^8 is released from the upward pull of chain H , and weight F^{10} will cause it to fall back on pin F^{18} and pull collar F^{11} , the negative carbon holder and carbon F^{14} downwardly until shoulder a strikes the upper face of F^6 . This action strikes an arc between the electrodes, the length of which is equal to the travel of collar F^{11} in F^6 . As the lower line of endless chain G is fastened to yoke F^7 and the upper line to bridge E^6 of the positive carbon mechanism, these points of fastening move in opposite direction when this chain moves on its rollers. The action heretofore described has moved the yoke F^7 and consequently also the chain fastened thereto upwardly. It moves thereby also the plate E^3 forwardly and with it the positive carbon. It should be noticed, however, that the movement of the chain G does not commence until lever F^8 and bushing F^{11} are fully lifted and that it ceases as soon as the hand is removed from H^4 .

This feeding action may be repeated as often as the arc requires an adjustment, it is independent of the length of either carbon, as the pull on the chain H will move them both until they meet and when released strike the arc. The screw F^{17} permits an adjustment of the negative carbon to bring it the required distance above bridge F^{15} to hold the arc in its proper place and to adjust for unequal burning of the carbons caused by varying density in the mass of the electrode. The whole lamp mechanism can easily be shifted by means of knob D^5 and rod D^4 on rods D^1 to vary its distance from the lens L .

In addition to the current entry through the carbon holders, the current is carried by plates E^{11} and F^{15} close to the points of both electrodes which permits a high current density at the arc in both electrodes.

The weight F^{10} is so placed that the arc striking action is not affected by tilting the lamp through an angle of 90 degrees.

The striking distance of the arc is so predetermined that the shortest satisfactory burning arc length for the current passing is struck. Inasmuch as there is no automatic feeding mechanism, the arc length increases with the time of burning. The required burning period in most cases for which this type of lamp is designed is normally so short that a second striking of the arc is unnecessary. However, where longer periods of operation are needed, an intermittent pull on the striking chain at 2 or 3 minute intervals will keep the lamp burning at a satisfactory constancy of light strength.

I claim:

1. In an arc lamp a pair of arc forming electrodes, a support for each electrode, a movable holder on one of said supports

- carrying an electrode, means on said holder to raise the electrode thereon while said holder is stationary, a stop to limit the raising movement, means to lift said holder
- 5 when the electrode is in raised position until the electrodes form a contact and means to lower the electrode in its holder to form an arc of predetermined length when said lifting means are released.
- 10 2. In an arc lamp a pair of arc forming electrodes, a support for each electrode, common means to move said electrode-supports simultaneously until the electrodes form a contact with each other, an electrode lifting lever on one of said supports forming means to move the electrode on said support, and other means to first operate said lifting lever, and then said means for moving the electrodes simultaneously.
- 15 3. In an arc lamp, a pair of arc forming electrodes, a support for each electrode, an endless chain arranged to move said electrodes toward each other and means adapted for remote manual operation to move said chain and said electrodes towards each other until their tips come together and means on one of said supports to open arc-space of fixed length between said electrodes upon release of said manually operated means.
- 20 4. In an arc lamp, a pair of arc forming electrodes, a support for each electrode, a movable holder on each support, means on one holder to lift the electrode thereon, a stop to limit the lifting distance, and means to feed both electrodes simultaneously towards each other connected to said lifting means and to the movable holders of both electrodes to lift the first electrode until said stop is reached and then to operate both electrodes for feeding.
- 25 5. In an arc lamp a pair of arc forming electrodes, a support for each electrode, a slideable holder for the electrode on each support and arc striking means on one of said slideable holders consisting of a member provided with a collar carrying the electrode and permitting limited longitudinal movement of said electrode, a chain adapted to lift said collar by manual operation and to bring the electrodes together and a weight 59 to hold said collar normally in lowered position and to open arc space between the electrodes.
6. In an arc lamp, a lamp housing, a pair of arc forming electrodes and a guiding 55 track within said housing, a carriage slidably supported on said track, said carriage holding a support for each electrode, means on one support for lifting the electrode, a stop to limit the lifting movement, feeding 60 means attached to the holders of both electrodes, means to operate said lifting means and said feeding means held on said carriage and means on the outside of said housing to slide said carriage on its track. 65
7. In an arc lamp, a lamp housing, a pair of arc forming electrodes within said housing angularly disposed to each other, separate guides for each electrode, electrode holders movable on said guides, common 70 feeding means to move both electrode-holders simultaneously on their guides, arc striking means on one electrode holder and common means extending without said housing to operate said feeding means and said arc 75 striking means consecutively by a single manual movement and its release.
8. In an arc lamp, an electrode support consisting of a guide bar, a plate slidably held thereon, a member having a collar slidably held on said plate to support an electrode, a swinging lever to move said member and to form gravity operated means for arc striking on said support, and means on said member to adjust said electrode in relation to said arc striking means. 80
9. In an arc lamp, an electrode support consisting of a guide bar, a plate slidably mounted thereon, a shouldered collar held in said plate, a carbon electrode supported 90 on said collar in axial alignment therewith, a lever on said support, a chain forming means arranged to raise said lever said collar and said electrode and a weight holding said lever normally in inoperative position. 95
